C. M. PAXTON

LUBRICATING SYSTEM FOR GYROSCOPES AND OTHER APPARATUS

Original Filed Nov. 12, 1920

UNITED STATES PATENT OFFICE.

CLIFFORD M. PAXTON, OF BROOKLYN, NEW YORK, ASSIGNOR TO PAXTON GYROSCOPE CORPORATION, A CORPORATION OF NEW YORK.

LUBRICATING SYSTEM FOR GYROSCOPES AND OTHER APPARATUS.

Application filed November 12, 1920. Serial No. 423,641. Renewed November 5, 1925.

My present invention was devised as a solution of certain problems in connection with proper lubrication of the spinning axles of the rotors used in gyroscopic apparatus, particularly where it is desired to balance the gyro rotor in neutral equilibrium or for operation in non-horizontal positions. Specific cases are the rotors of my so-called parallel gyros described in various of my applications, as for instance Serial No. 417,602, filed Oct. 18, 1920; and also the meridian gyros, as for instance those shown in my application Serial No. 420,372, filed Oct. 27, 1920. The conditions in the latter case are the most exacting of all since here the gyro shaft operates to maintain fixed direction in space in a plane at right angles to the earth and hence considered with relation to earth's verticals, must be capable of rotating end over end.

Being designed to operate perfectly under the extremely exacting conditions above described, it is obvious that many features of the invention will be useful when embodied in bearings for other purposes, including those where the shaft is maintained either horizontal or vertical or those where there is no necessity for balancing the rotating parts in neutral equilibrium.

As applied to the specific case of the gyro scope rotor adapted to be balanced in neutral equilibrium on horizontal pivots at right angles to the axis of the rotor, the primary difficulty is to maintain an adequate supply of lubricating oil in operative relation to the bearings without causing the weight of the oil supply to shift the center of gravity when the inclination of the spinning shaft is shifted. For instance, if a reservoir supply of oil is maintained beneath each of the spinning bearings, gravity causes oil in the up-tilting reservoir to gravitate toward the pivotal axis, while that on the down-tilting side gravitates away from the tilting axis, even though the amounts of oil be precisely equal. This shifts the leverages with respect to the pivotal axis, so as to destroy the balance.

My invention solves this problem by arranging each lubricating cavity concentrically with the spinning axis in such relation that the spinning shaft acts centrifugally on the entire supply of oil in each cavity to force it into the form of a symmetrical ring or annulus surrounding the spinning shaft whenever the latter is in operation. Such centrifu-

gally maintained oil rings are at fixed distances from each other and may be centered with respect to the mounting axes as certainly as can any solid metal parts of the device. By this method the leverage of the surplus oil with respect to the tilting axis is always the same during operation of the device, and it is only necessary to keep the weights of the oil approximately the same to assure perfect balance during spinning. When the rotor is no longer spinning, the oil will of course gravitate as in any other reservoir system, that is to say, it will be in balance when the spinning axis is horizontal, but out of balance when the spinning axis is inclined. The point is that during operation the two bodies of oil are each held in rigidly fixed position by centrifugal force so that the spinning axis can be turned end over end, without any gravitational effect on the oil, and hence without any disturbance of the balance.

By this method the oil is centrifugally forced into contact with the ball or other bearing surfaces so that the lubrication is the most perfect possible.

Another feature of the invention is providing an annular pocket around the spinning shaft opening, in which the surplus oil will be trapped and prevented from escaping even if the spinning axle be turned end over end when the gyro is not spinning.

Another feature of my invention consists in employing ball bearings mounted in journal boxes formed for the purpose of retaining oil as above described, each journal box being adjustable in a direction parallel with the spinning axis, preferably by means of a set screw. Thus the rotor and shaft can be endwise adjusted for perfecting balance by merely screwing up or backing off the two screws correlative. A minor feature of the invention is utilizing said set screws as conduits for introducing the oil supply into the housing of the bearing. Another feature is arranging the inlet in the form of a nipple so that there will be no tendency for reverse leakage when the rotor is not operating and the set screw through which the oil was introduced is inclined downward.

The above and other features of my invention will be more fully understood from the following description in connection with the accompanying drawings, in which:

Figure 1 is a side elevation, partly in axial

section, showing a gyroscope rotor unit embodying my invention;

Figure 2 is a face view of a modified construction of one of the parts shown in Figure 1;

Figure 3 is a section on the line 3, 3, Figure 2;

Figure 4 is a longitudinal section of a modified form of my invention adapted for 10 use where the shaft extends entirely through the journal box.

In Figure 1 the invention is shown as embodied in a gyro rotor unit. The peripheral casing 1 is closed in by heads 2, 2 secured 15 by screws 3, 3 formed with housings 4, 4, closed by screw caps 5, 5, containing the roller bearing journal boxes. The casing 1 is provided with horizontal pivotal trunnion 6 about which the unit may be rotated to 20 permit of any desired inclination of the rotor shaft 7 with respect to the horizontal indicated by dotted line X—X.

The rotor on shaft 7 and the motor for driving the same may be of any known or 25 desired construction. Ordinarily, however, the rotor will be fairly heavy, say 8 to 17 lbs. and adapted to be rotated at fairly high speed, say 3,000 to 9,000 revolutions per minute; and the motive power will be a three- 30 phase induction motor having the armature built in as part of the rotor and the field rigidly secured to the casing.

Within the housings 4, 4, and caps 5, 5, are 35 located the shaft bearings, the parts in the housing 4 and cap 5, at the left hand end of the gyro casing being preferably similar in construction, and oppositely or symmetrically located with respect to those shown in section at the right hand end. While the shaft 40 bearing may be built into the housing, I prefer a separate journal box comprising a casing member 8 and a cover 9 secured thereto by screw threads 10, oil-tight packing being interposed, if desired. The exterior periphery of the journal box is preferably circular 45 to fit the housing 4, but convex longitudinally so as to permit forcing of a slight rocking adjustment of the journal box, to align the bearing axis with the shaft axis, when the 50 journal box is adjusted longitudinally. This is preferably accomplished by set screw 11 engaging a seat 12 centrally located on the journal box cover 9. Screw 11 is held in desired position of adjustment by lock nut 55 12'.

Interiorly the journal box 8 is accurately machined to receive the outer band 13 of a roller bearing unit of any known or desired construction. Such units are usually pur- 60 chasable in the market, with the box bearing ring 13, journal bearing ring 14 and balls 15, 15 already assembled, as shown in the drawing. The bearing band 13 preferably fits the journal member 8 very accurately and 65 the latter is preferably provided with a lip 16

so that when bearing band 13 is force-fitted in position, it will be rigidly held and the surfaces of contact will be oil-tight.

The journal bearing 14 is mounted on the end of shaft 7 preferably by being force-fitted over a sleeve 17 which is in turn accurately coned to fit over a cone projection 18 and against a shoulder 19 formed on the end of shaft 7.

The interior of the journal box 8 and cover 75 9, is contoured so that the interior of the bearing band 13 is in effect the peripheral bottom of the cavity so that when the oil is driven outward by centrifugal force, as hereafter described, the ball race in ring 13 will 80 be bathed in the oil until the last traces of the excess oil supply have been used up.

The escape of oil from the cavity is prevented without the need of any joint between moving parts, or any stuffing box or any other 85 packing such as is commonly employed for such purposes. This is accomplished by forming the journal box 8, adjacent the inner opening through which shaft 7 projects, with a collecting and draining groove 20. This 90 is made large enough to hold the excess oil supply when the shaft 7 is not spinning, and when the shaft is spinning, escape of oil is prevented by arranging on said shaft 7, preferably as an integral extension of 95 bushing 17, a rotor 21, formed with a surface 22 closely adjacent the internal surface of the cavity in the journal box 8. The clearance between these surfaces, as preferably the clearance 100 between the end of the shaft 7 and the journal box cover 9, is very small so that any intervening layer of oil will be very thin, preferably not much more than a mere film, so that when the shaft is spinning at high speed the rotating surfaces adhering to the 105 oil will powerfully propel the latter outward, away from the shaft axis and the shaft opening in journal box 8, thus operating as a very efficient centrifugal pump. So far as concerns the centrifugal pump effect at the end 110 face of shaft 7, this is important only as making certain that the last drop of oil in the reservoir will be used up before the bearings can go dry. The similar action by rotor 21, however, is much more important, since it 115 will be evident that where sufficient oil is used to more than wet the surfaces, that is, sufficient to afford a desired reserve-supply, the rolling of the balls around the bearing surfaces at less than the peripheral speed of the 120 pump rotor, will naturally tend to equalize the peripheral speed of the oil and also to deflect the oil laterally from under the balls and out of the groove or ball race in which they roll. In such case the laterally driven 125 oil will be continuously forced back and held in the ball cavity by the centrifugal pumping action, and particularly such oil as attempts to pass outward over the rotor pump surface 22 will be effectively prevented from 130

splashing around to the exterior, by the powerful centrifugal pump action of said surface 22, the peripheral speed of which will be more than twice that of the balls.

5 From the above it will be seen that the reservoir capacity of the journal box cavity will be very great where the device is to be used with cover 9 lowermost, but where the device is frequently used with the shaft 10 opening downwardly directed, as in the case of a gyroscope unit of the above described class invented by me, the reservoir capacity will be limited to the amount of oil that will lie in the groove 20 when the shaft is not 15 spinning. For gyro purposes this is amply sufficient, since a teaspoonful or, if desired, a tablespoonful, or more, of excess oil can be retained when in this position and as none of it can ever be lost out of the journal box 20 the supply will be ample for long periods of running. Obviously, however, the groove 20 may be made of much greater depth so that it will hold a much larger quantity of oil without the possibility of spilling. Moreover, 25 the pump rotor surface 22 may be cut away as indicated in Figures 2 and 3 so as to leave only centrifugal pump blades 22' to invade the oil retaining groove 20. Thus, all the space between blades 22' becomes available for holding an additional supply of oil.

While it is perfectly possible to insert the required supply of oil in the journal box cavity by removing caps 5 and cover 9, a desirable detail of my invention includes arranging an oil inlet duct 31, the exterior end of which is provided with screw 32 serving as a removable closure and the inner end of which communicates with passage 33 extending through cover plate 9 and a nipple 40 34 formed on the inner surface thereof. This nipple extends a considerable distance into a cavity 35 on the end of shaft 7. Thus with this arrangement the oil may be induced through passage 31, preferably by gravity, 45 the casing 1 being turned about trunnion 6 to bring screw 11 into the vertical position. If subsequently the device is restored to the position shown in Figure 1, or even if it is turned still further downward to a position 50 where all of the oil collects on the inner surface of cover 9, nevertheless the stand pipe nipple 34 will prevent gravity flow of oil through passage 33. This is desirable since the seat of screw 11 in cavity 12 is not necessarily oil-tight. An escape of oil from this 55 point may be undesirable. Of course when the shaft is spinning the oil is kept away from stand pipe 34 by the centrifugal pumping effect of the end face of the shaft. Such end faces of the shaft may be formed with pumping blades on the principle illustrated in Figures 2 and 3.

It will be evident that at all times when the shaft 7 is spinning the oil will be centrifugally maintained in a stable ring formation

adjacent the surface of bearing band 13 and that the device as a whole may be balanced in neutral equilibrium on trunnion 6 regardless of changes of angular position of the shaft axis.

Such balancing is easily effected, because as above described the parts at the left hand end of the casing, in Figure 1, are oppositely and symmetrically arranged with respect to those at the right hand end, and with this arrangement the shaft 7 and all parts carried thereby can be adjusted endwise by comparatively backing off and screwing up the adjusting screws 11.

In Figure 4 I have shown a modification in which the parts are all the same, except that the shaft 7^a extends entirely through the bearing box 8 and the housing 4^a, 5^a. Moreover the housing and shaft are not necessarily parts of a gyroscope, but may be any shaft and bearing for any purpose whatever. In this case the journal box 8, ball bearing members 13, 14 and 15 and rotor 21 with centrifugal pumping surface 22 may be the same as before. In the present case, however, the shaft extends through the cover 9^a corresponding to cover plate 9, hence cover plate 9^a is formed with oil-retaining groove 20^a, and an additional pumping surface 22^a is provided similar to and symmetrical with 22. Such a form of lubricated ball bearing is particularly useful in connection with high speed motor or hand-operated drills, egg beaters, stirrers, mixers, adjustable electric fans or any and all similar devices where lubricated ball bearings are desirable, particularly where the shafts are intended to be used in a vertical or inclined position.

I claim:—

1. A gyro unit comprising gyro rotor, shaft and bearings, in combination with an enclosing support for the bearings affording, with said bearings, an interior circular lubricating cavity having an exterior opening of lesser diameter through which the shaft extends, and a pump rotor on said shaft, rotating in close proximity to peripheral as well as radial walls of said cavity to pump oil radially away from the shaft opening and laterally into the bearing when said shaft is running.

2. A gyro unit comprising gyro rotor, shaft and bearings, in combination with an enclosing support for the bearings affording, with said bearings, an interior circular lubricating cavity having an exterior opening of lesser diameter through which the shaft extends, and a rotor on said shaft, the surface of said rotor fitting the wall of said cavity with thin clearance space between them and both being transversely curved to force the oil laterally as well as radially away from said shaft opening.

3. A gyro rotor unit comprising supporting means, rotor, shaft and end bearing boxes

for the shaft mounted so as to be longitudinally adjustable in said support and oppositely directed axially aligned adjusting screws engaging the opposite ends of said bearing boxes, said parts being formed with oil ducts traversing the adjusting screws and the portion of the bearing box with which the ends of said screws are in contact.

4. In the combination specified by claim 3
10 the further feature of screw closures for the outer ends of said ducts.

5. In the combination specified by claim 3
15 the further feature of standpipe element through which said oil duct discharges, projecting axially within the box bearing cavity.

6. A gyro rotor unit comprising supporting means, rotor, shaft, end bearings, boxes for the shaft mounted so as to be longitudinally adjustable in said support, and oppositely directed axially aligned adjusting screws engaging the opposite ends of said bearing boxes, said bearing boxes each being provided with an interior oil reservoir cavity designed with reference to the rotating parts
25 so that the latter have a centrifugal pumping effect to maintain excess oil in the peripheral portion of the cavity while the rotor shaft is spinning, regardless of the angular position of said shaft.

30 7. A gyro rotor unit comprising rotor, shaft, bearings, and a horizontally pivoted casing in which said parts are mounted, said bearings each including roller bearings and a journal box affording an interior circular lubricating cavity having an exterior opening of lesser diameter through which the shaft ex-

tends; together with a rotor on said shaft concentric with said cavity operating as a centrifugal pump to force oil away from the shaft opening when said shaft is running; 40 and means for comparatively adjusting said journal boxes and with them the oil, roller bearings, shaft and rotor carried thereby, to balance said unit with respect to its horizontal pivots.

45 8. In the combination specified by claim 7, the further feature of an inwardly directed oil-retaining groove or cavity surrounding the shaft opening.

9. In the combination specified by claim 7, 50 the further feature of having the rotor pumping element extend into operative pumping relation to oil collecting in said groove.

10. A gyro unit comprising rotor, shaft and bearings, in combination with an enclosing support for the bearings affording, with said bearings, an interior circular lubricating cavity having an exterior opening of lesser diameter through which the shaft extends and ball bearings between the shaft and support 60 and a pump rotor on the shaft, said shaft, bearings, balls and pump rotor substantially filling said lubricating cavity so that substantially all the oil in the cavity is maintained in a peripheral ring of substantially equal radial thickness, around the entire circumference of said cavity.

65 Signed at New York, in the county of New York and State of New York this 11th day of November, A. D. 1920.

CLIFFORD M. PAXTON.
